SPIKE PULLER

George W. Johnson, Canton, Ohio, assignor to
The Bowdil Company, Bowdil, Ohio, a corpora-
tion of Ohio

Application February 16, 1933, Serial No. 657,137

11 Claims. (Cl. 254—25)

This invention relates to spike pullers and has for its object to provide a comparatively simple and inexpensive device of this character embodying in its structure a rocking fulcrum whereby to increase the leverage and permit extraction of a spike from a cross tie or other support with greater facility and less exertion on the part of the operator than heretofore.

A further object is to provide a spike puller having a claw detachably secured in position on the head of the implement so as to permit the ready removal thereof to facilitate dressing when necessary or replacement by claws of different sizes according to the size of the spike or other fastening to be extracted.

A further object is to provide a hand tool of this character the construction of which is such that a spike may be quickly pulled or extracted without the necessity of the operator bending over the work and in which the extracting claws are relatively small and made of high grade steel so as to increase the effective life of the tool.

A still further object of the invention is generally to improve this class of devices so as to increase their utility, durability and efficiency.

In the accompanying drawing forming a part of this specification:

Figure 1 is a side elevation of a spike puller constructed in accordance with the present invention and showing in full lines a claw positioned over a spike and in dotted lines the position assumed by the parts when the tool is rocked on its fulcrum to pull the spike.

Figure 2 is a vertical sectional view of the head of the implement and its associated parts.

Figure 3 is a transverse sectional view taken on the line 3—3 of Figure 2.

Figure 4 is a bottom plan view of Figure 2.

Similar numerals of reference indicate corresponding parts in all the figures of the drawing.

The improved spike puller forming the subject matter of the present invention comprises a hollow cylindrical head 5 preferably formed of metal and of any desired length and cross sectional diameter, said head being provided with an upstanding boss 6 the interior walls of which are threaded at 7 and adapted to engage the correspondingly threaded end 8 of an operating lever 9. The lever 9 is preferably cast or otherwise formed with longitudinal strengthening ribs 10 and terminates at its outer free end in a smooth portion constituting a handle 11. The head 5 is provided with oppositely disposed seating recesses 12 in which is detachably fitted a removable claw indicated at 13. This claw 13 is relatively small so as to permit the claw to be made of high grade steel at very little additional cost and the opposite ends of the claw

are curved or deflected upwardly to form curved terminals 14 having seats 15 and 16 formed therein and adapted to receive a spike indicated at 17. The lower surface of the head 5 constitutes a fulcrum 18 on which the implement is rocked in the act of pulling or extracting a spike and immediately above the fulcrum 18 the head is provided with a flat bearing surface 19 preferably disposed at a slight angle to the horizontal axis of the head, as shown. The lower surface of the claw 13, where it rests on the flat surface 19, is cut away to form oppositely disposed shoulders 20 which bear against the exterior wall of the head and serve to center the claw within said head. The upper surface of the claw is preferably formed with a shallow concave socket 21 and the recesses 12 are slightly larger than the thickness of the claw so as to permit the claw to be inserted within the head from either side thereof. That portion of the operating lever immediately below the threads 8 terminates in a smooth cylindrical extension 22, the lower face of which is convex and is adapted to enter the concave seat 21 whereby when the lever 9 is rotated, the convex end of the extension 22 will bear against the claw and firmly clamp said claw within the head. A nut 23 engages the threads 8 on the lever and bears against the adjacent end of the boss 6 for locking the lever against rotation after said lever has been adjusted to clamp the claw within the head.

The lever 9 is preferably of sufficient length to permit the operator to position the claw over a spike and extract the same without the necessity of bending over the work and thus permits the extraction of a spike with very little exertion on the part of the operator. The spike engaging seat 16 is preferably larger than the seat 15 so as to permit the tool to be used for extracting spikes of different sizes and inasmuch as the claw 13 is detachably mounted in the head, said claw may be readily removed therefrom to permit dressing or replacement by claws of different sizes according to the nature of the work to be performed. Attention is called to the fact that the lower curved faces 24 of the claw are curved to conform to and form a continuation of the curved surface of the fulcrum 18 so as to permit free rocking movement of the tool in either direction on a cross tie when pulling or extracting a spike therefrom.

In operation, the implement is positioned adjacent the spike to be extracted with the head of the spike seated in either one of the seats 15 or 16, as shown in full lines in Figure 1 of the drawing. The handle 11 is then pulled rearwardly to the dotted line position shown in Figure 1, which causes the fulcrum 18 to rock on the cross tie or other support and lift or extract the spike therefrom. If a larger spike is to be extracted,

- the claw 13 may be readily removed by releasing the clamping nut 23 and rotating the lever 9 until the cylindrical extension 22 is disengaged from the claw when, by elevating the claw slightly to permit the shoulders 20 to clear the head 5, said claw may be readily removed from the head from either side thereof through the adjacent seating recess 12. In fitting a new claw to the head it is merely necessary to reverse the operation, that is to say, insert the claw within the head through either recess 12 and position the shoulders 20 over the adjacent wall of the head and then rotate the lever until the extension 22 enters the socket 21, when the claw will be firmly clamped in position on the head and in which position it may be rigidly supported by adjusting the nut 23. With a tool constructed in this manner, a plurality of claws may be kept in stock and a desired claw selected from the stock and inserted in the head according to the work to be performed. Therefore the head and its associated parts may be used for an indefinite period as the only part which needs renewal is the claw. It will, of course, be understood that the tool may be made in different sizes and shapes and constructed of any suitable material without departing from the spirit of the invention.
- Having thus described the invention, what I claim is:
1. An implement of the class described comprising a substantially cylindrical head, a reversible claw detachably secured on the head, a handle threaded through the head and engaging the claw for securing the claw in position thereon, and means carried by the claw and engaging the head for preventing lateral displacement of said claw.
2. An implement of the class described comprising a hollow substantially cylindrical head having oppositely disposed recesses formed therein, a removable extracting claw seated in said recesses, an operating handle threaded in the head and bearing against the claw for clamping the claw in position on the head, and means on the claw engaging the head at the recesses therein for preventing lateral displacement of said claw.
3. An implement of the class described comprising a hollow substantially cylindrical head having oppositely disposed recesses formed therein, a detachable claw fitted in said recesses and provided with spaced shoulders bearing against the head, and an operating handle having a threaded portion extending within the head and bearing against the claw for clamping the claw in position on the head.
4. An implement of the class described comprising a substantially cylindrical head, a removable extracting claw seated in the head and having its opposite ends curved upwardly, the lower curved portion of the head between said upwardly curved portions constituting a fulcrum, an operating lever extending within the head and bearing against the claw for detachably securing the claw in position on the head, and means independent of the lever for preventing lateral displacement of the claw within the head.
5. An implement of the class described comprising a head, the lower portion of which is curved and constitutes a fulcrum, a removable extracting claw fitting within and extending transversely of the head, an operating lever threaded in the head and bearing against the

claw for clamping the claw in position on the head, and means on the claw coacting with the head for preventing lateral displacement of said claw.

6. An implement of the class described comprising a hollow cylindrical head having an internally threaded boss projecting therefrom, a removable claw carried by the head and extending transversely thereof and having its upper surface provided with a socket, and an operating handle having its lower end threaded in the boss and provided with a terminal convex end adapted to fit within the socket and clamp the claw in position on the head. 80

7. An implement of the class described comprising a hollow cylindrical head having oppositely disposed recesses formed therein and provided with a threaded boss, a detachable claw carried by the head and removable therefrom through either recess, an operating handle having a threaded portion engaging the threads in the boss and bearing against the claw for clamping the claw in position on the head, and a nut engaging the threads on the operating handle and bearing against the boss. 85

8. An implement of the class described comprising a hollow cylindrical head provided with oppositely disposed recesses and having its lower portion provided with a flat bearing surface disposed at an angle to the horizontal axis of the head, a removable claw having a flat lower surface engaging the flat bearing surface and defining oppositely disposed stop shoulders for contact with the head, and an operating handle threaded in the head and having its lower portion 100 bearing against the claw for securing said claw in position on the head.

9. An implement of the class described comprising a hollow cylindrical head having oppositely disposed recesses formed therein, a detachable claw seated in said recesses and having its opposite ends deflected upwardly and provided with lower curved surfaces, the exterior surface of the head between said ends forming a continuation of said lower curved surfaces and 115 constituting a fulcrum, and an operating handle extending within the head and bearing against the claw for detachably securing the claw in position on the head. 120

10. An implement of the class described comprising a head having a cylindrical portion constituting a rocking fulcrum, an extracting claw removably fitted within the head and provided with spaced shoulders, and an operating handle extending within the head and bearing against 130 the claw for clamping the shoulders in engagement with the head. 125

11. An implement of the class described comprising a hollow head having a cylindrical portion constituting a fulcrum and provided with 135 oppositely disposed seating recesses, a removable extracting claw fitted within said recesses and provided with spaced shoulders defining terminal upwardly deflected portions disposed on opposite sides of the fulcrum and having spike receiving 140 seats formed therein, and an operating handle threaded in the head and having a terminal portion adapted to bear against the claw and clamp said shoulders against the head on opposite sides of the fulcrum. 145
